THREAD GRINDING AND GRINDING WHEEL
DRESSING DEVICE

Stanley Wallace, Des Plaines, Ill.

Application March 8, 1945, Serial No. 581,581

27 Claims. (Cl. 125—11)

1

This invention is concerned with improvements in contour-grinding, thread-grinding and grinding wheel dressing devices.

The device made in accordance with the invention is adapted for use in grinding in an efficient and accurate manner internal and external surfaces of different contours, for example, desired threads, and is equipped with a mechanism for accurately dressing the grinding wheel which may at any time be used for grinding the desired surface or thread.

One of the objects of the invention is concerned with the provision of a grinding and dressing device of the character noted herein, which is adapted for use with machine tools, for example, lathes, shapers, planers, or the like.

Another object resides in the provision of a dressing device in combination with a grinding mechanism, which dressing device is so constructed and arranged that the grinding wheel may be accurately dressed and its contour maintained without changing or disturbing the work set-up.

Still another object is concerned with the provision of a device for dressing grinding wheels adapted to produce angular or square, external or internal threads, as well as grinding wheels adapted to produce concave, convex, spherical, irregular or tapered surfaces.

Additional objects and features will be brought out in the course of the detailed description which is rendered herein with reference to the accompanying drawings. In these drawings,

Fig. 1 is a front view of an embodiment of the new grinding and dressing device and associated parts, as seen from the position of the operator;

Fig. 2 illustrates a top view as seen along the lines 2—2 in Fig. 1, with some parts broken away to show details;

Fig. 3 represents a sectional view of the dressing device taken approximately along lines 3—3 in Fig. 1;

Fig. 4 shows a partial end view as seen from the right along lines 4—4 in Fig. 1;

Fig. 5 illustrates a sectional view taken approximately along lines 5—5 in Figs. 1 and 2;

Figs. 6 and 7 are sections through a dressing guide taken along lines 6—6, 7—7 in Fig. 3;

Fig. 8 shows in diagrammatic perspective view an embodiment of an adapter for use with certain dressing devices, for example, devices for dressing grinding wheels employed in grinding internal threads;

Fig. 9 illustrates the adapter of Fig. 8 in full

2

lines in operative position and in dotted lines in retracted position;

Fig. 10 represents a diagrammatic top plan view of an example of a dressing device for dressing grinding wheels having a shaped or irregular contour,

Fig. 11 shows a section through the device illustrated in Fig. 10 along lines 11—11 thereof;

Fig. 12 is a diagrammatic top plan view of a device for dressing grinding wheels such as are used for grinding so-called "Acme" threads, having two flanks or sides which converge into a flat surface; and

Fig. 13 illustrates some of the elements of Fig. 12, partially in section, to explain the operation of the structure.

The invention is not limited to use in connection with any particular type of machine tool, but is shown for convenience with the compound slide of a lathe. The compound slide may be mounted in conventional manner on a cross-slide. Only part of the compound slide of the lathe is diagrammatically indicated in the drawings. All other parts of the lathe are omitted.

The new device comprises several principal parts which are assembled to form a unitary mechanism. These principal parts include (1) the grinder mechanism comprising a quill containing a spindle which carries the grinding

30 wheel; (2) a mounting member for the quill and for the motor which operates the spindle; (3) a bracket for adjustably supporting the mounting member (and therewith the grinder mechanism) on the compound slide of the lathe; and (4) the 35 grinding wheel dressing device which is mounted on a frame supported by the quill and radially extending therefrom.

The motor and quill mounting member 1 is provided for holding the motor 2 (shown in Fig. 1 in dotted lines), which drives a belt 3 to rotate a shaft or spindle 4 journalled in the quill 5. The grinding wheel 6 is attached to the shaft 4 at the left end thereof, as is particularly apparent from Figs. 1—3. These parts constitute the 45 grinder mechanism.

The motor and quill mounting member 1 is supported on a post 7 provided with a flange 8 (Fig. 5) which in turn is angularly adjustable with respect to a holder 23. A screw 9 is provided for 50 effecting the angular adjustment of the post 7 (flange 8) on the holder 23. An elevator screw 14 is adapted to lift or to lower the holder 23 and therewith the motor-quill assembly supported on the post 7. The elevator screw is carried by the 55 upright wall 11 of a mounting bracket having a

base 12 and side walls 13. The base 12 may be adjustably mounted on the compound slide of the lathe. The adjustment of the holder 23 and parts attached thereto is secured by the nut 10. The motor-quill mounting member 1 can thus be placed in a desired position vertically and can be adjusted angularly in any vertical position thereof. These parts constitute the mounting for the grinder mechanism. The quill 5 and therewith the grinding wheel 6 are therefore adjustable vertically and angularly in a vertical plane.

The angular adjustment of the mounting member 1 holding the motor-quill assembly permits setting of the grinding wheel 6 to the helix angle of the thread to be ground. The elevator screw 14 permits vertical adjustment of the assembly 15 for the purpose of positioning the grinding wheel 6 with respect to the work piece.

The base 12 of the mounting bracket on the upright wall of which the motor-quill assembly is adjustably secured, as described above, is angularly adjustably mounted on an index plate 15 by means of a screw 16 which engages a nut 17 disposed in the lower part of the slot in the compound slide 18. An extension 19 (Fig. 1) depending from the index plate 15 engages the upper part of the slot in the compound slide. The index plate 15 is thus fixed on the compound slide, and the base 12 of the bracket is held thereon in a position which is angularly adjustable in a horizontal plane.

The compound slide 18 is disposed at an angle with respect to the cross-slide of the lathe, as shown in Figs. 1, 2 and 4. Fig. 4 also shows the gib screws of the compound slide without, however, identifying them by reference numerals.

The understanding of the structure, use and operation of the device will be facilitated if the following features appearing from the above general description are kept in mind: (1) the compound slide 18 is adjustable in a horizontal plane at a desired angle to the cross-slide, in order to permit feeding the grinding wheel 6 with respect to the work-piece on a line which is substantially in parallel with the flank or side of the thread to be produced. This adjustment tends toward economy and accuracy of the thread-grinding operation; (2) the mounting bracket carrying on its upright extension 11 the motor-quill assembly is angularly adjustable on the compound slide in a horizontal plane, in order to compensate for the angular setting of the compound slide with respect to the cross-slide, permitting also additional angular setting of the entire mechanism for the purpose of placing the quill and associated parts so as to clear the tail stock of the lathe; (3) the grinding wheel assembly may be vertically moved to an adjusted position in which the point of contact on the grinding wheel is properly aligned with the center of the work-piece; and (4) the assembly may be angularly tilted in a vertical plane, and may be fixed in adjusted position by means of the screw 9 and nut 10, for the purpose of properly placing the grinding wheel to determine the helix angle of the thread to be produced by it.

Attached to the quill 5, near the end which is adjacent the grinding wheel 6 (see left hand end of Figs. 1 and 2) is a frame on which is mounted the dressing device for the grinding wheel. This device with its associated parts is generally designated in Figs. 1-4 by reference numeral 20.

Structural details will now be explained mainly with reference to Figs. 1-5, taking into account

the sequence of setting-up operations required for producing, for example, an external 60° thread on a plug gage. It should be noted, however, that the sequence of setting-up operations, as explained below, indicates only an example, permitting deviations that may be required or desired in practice.

The setting-up of the device is initiated by removing from the compound slide 18 the usual tool post and inserting in its place, in the slot of the slide, the nut 17. The index plate 15 is next placed on the compound slide with its extension 19 depending into the upper portion of the slot thereof. The mounting bracket, which 10 may be a cast structure having the base 12, side walls 13 and upright wall 11, is next placed on the plate 15 and is preliminarily clamped into position by means of the screw 16 which is in threaded engagement with the nut 17. An index tongue 21 is provided in a suitable groove in the base 12 of the mounting bracket for alignment with the peripheral index markings on the plate 15.

The upright wall 11 of the mounting bracket is provided with a vertically extending elongated slot or opening 22 (Figs. 1 and 5) adapted to accommodate the holder 23 which is slidable therein responsive to actuation of the elevator screw 14. This screw engages a threaded hole 25 on top of the vertically extending portion 11 of the mounting bracket and carries at its lower end a head 24 which is inserted in the holder 23 from beneath through an opening 25. It should be noted that the thickness of the bracket extension 11 exceeds that of the holder 23. The face of holder 23 is thus slightly recessed with respect to the plane of the front wall of the bracket extension.

The screw 9 extends through a transverse opening 40 in the holder 23 into threaded engagement with the post 7. Numeral 26 indicates an index tongue projecting from the holder 23 for alignment with index marks on the periphery 27 of the flange 8 of the post 7. The screw 9 is provided with an enlargement 28 for engagement with the face of holder 23. Accordingly, when the screw 9 is tightened in its threaded hole in the post 7, the post will be firmly clamped to the holder. The angular adjustment of the post 7 45 can thus be secured independent of the vertical adjustment thereof. The latter is effected by rotating the screw 14 to shift the holder 23 and with it the post 7 vertically within the slot 22 in the mounting bracket to any desired position 50 therein. After the required angular and vertical adjustments are made, as will be presently described in detail, the assembly is secured in position by tightening the nut 10, thereby clamping the post 7 firmly in position on the mounting bracket. At this preliminary stage of 55 the setting-up operation, the post is merely put on the bracket extension 11 without any but preliminary and approximate attention to its vertical and angular position.

The mounting post 7 is now ready to receive the motor-quill mounting member 1. This member is attached by slipping it onto the post 7, as is particularly indicated in Fig. 5. The clamp screw 30 60 (Figs. 2 and 4) is for this purpose loosened in order to permit proper placement of member 1 on the post 7. Numeral 31 in Fig. 5 indicates a clamping sleeve by means of which the assembly is secured on the post 7 responsive to tightening of the screw 30. The proper joining of the motor-quill member 1 with the post 7 and attachment

5

thereof to the post are obtained by the lock-pin 32 (Fig. 2) which extends from the motor-quill mounting member 1 and is accommodated in a suitable hole in the flange 8. The mounting member 1 is now put in preliminary approximate angular position by loosening the screw 9 and nut 10, if necessary, and rotating the assembly and therewith the post 7, whereupon the screw 9 and nut 10 are preliminarily tightened.

The frame 33 of the dressing device 20 is provided with a rearward extension forming a split tubular holder 34 comprising the sections 35—36 and a rearwardly extending bracket 37. The tubular holder is slipped onto the left end of the quill 5, as seen in Figs. 1 and 2, with the bracket 37 in alignment with a boss 38 projecting from the quill. A screw 39 is provided for fastening the bracket 37 to the boss 38 and another screw 39a (Fig. 1) is employed for tightening the sections 35—36 of the tubular holder on the quill in the manner of a clamp.

The next step in setting up the mechanism includes attachment of the grinding wheel 6 to the spindle 4 by means of the nut 40. Numeral 41 indicates suitable washers between which the grinding wheel is clamped on the spindle 4.

The laterally forwardly projecting part of the frame of the dressing device comprises the bottom portion 42 forming slide surfaces or ways 43 (Figs. 2 and 3), the rearmost way or slide surface terminating in the upward projection 44. The extension 33 forming the previously mentioned split tubular holder 34 is also provided with an apron 45 disposed below the grinding wheel 6 and with a top apron 46 disposed thereabove, the latter terminating in a dust shield 47.

The dressing frame described above accommodates on its ways 43 a compensating plate 48. This plate is secured in place by means of screws 49—50 extending upwardly through elongated slots 51—52, respectively, in the ways 43. The compensating plate 48 may thus be laterally shifted on the ways 43 of the frame and may be secured in any laterally adjusted position. The forward end of the compensating plate may be suitably curved and may be provided with index marks, as shown in Figs. 1 and 2. This compensating plate serves as an adjustable support for the dressing head and permits lateral setting of the dressing points so as to obtain proper alignment with the grinding wheel, and angular setting of the dressing head so as to effect positioning of the feed line of the dressing points perpendicular to the axis of the work-piece.

The dressing head comprises a bottom portion 53 carrying a pivot pin 54 which extends in pivotal relation into a hole 55 in the compensating plate 48, as shown in Fig. 3. The compensating plate 48 is also provided with an arcuate slot for receiving the screw 56 which is in threaded engagement with the bottom plate 53. The dressing head can thus be adjusted angularly on the compensating plate and can be fixed in any angularly adjusted position. An index member 57 projects forwardly from the bottom plate 53 into a position relative to the index marks on the forward end of the compensating plate 48. The amount of angular adjustment of the dressing head on the compensating plate is thus visually indicated. The bottom wall 42 of the dressing frame is also provided with an arcuate slot for accommodating the screw 56 in any angular position thereof.

The bottom plate 53 of the dressing head terminates in a front wall 58 in which is rotatably journalled the forward end 59 of the feed screw,

6

the rear end of which is threaded as shown at 60. Numeral 61 in Fig. 3 indicates a bearing sleeve, which is attached to the screw by means of a pin 62. The forward end 63 of the feed screw is provided with calibrations and with a knurled knob 64. Rotation of this knob causes rotation of the screw and its threaded extension 60 in an obvious manner. The degree of rotation is indicated by the calibrations or index markings on the forward portion of the screw relative to a suitable index mark on the front wall 58.

The threaded portion 60 of the feed screw is in threaded engagement with the feed nut 65, also shown in Fig. 3, which in turn is attached to the top plate 66 by means of the screw 67. Therefore, rotation of the feed screw causes shifting of the feed nut and therewith shifting of the top plate 66 relative to the base plate 53. The top plate 66 is provided with downwardly depending ears 70—71, one on either side thereof, and these ears carry holes for sliding engagement with guide posts 68—69 shown in Fig. 1. These posts are mounted in the front wall 58 of the base plate 53. They serve the purpose of securing the top plate 66 in proper sliding position and of avoiding angular distortion of the sliding motion that may otherwise be induced by rotation of the feed screw.

The top plate 66 is provided near its rearward end with a threaded hole for receiving the screw 72 which holds the dressing guide on the dressing head. The dressing guide is that part of the mechanism which carries means, e. g., diamonds, for abrasive engagement with the grinding wheel. This dressing guide is removably mounted on the dressing head, but may be made integral therewith, if desired.

The above described structure of the dressing head, comprising the base plate 53 with its feed screw 60 journalled at 59 and provided with a knob 64, and including the top plate 66 with its feed nut 65 and its depending sides or guide flanges 70—71 engaging posts 68—69, may be used for supporting any one of a number of dressing guides that may be required in the practical use of the device for dressing grinding wheels of different contours.

It will be clear from the foregoing explanations that the dressing head (and with it any dressing guide that may be mounted thereon) is pivotally supported on the compensating plate 48 by means of the pivot pin 54, and that it can be fixed in any angularly adjustable position by means of the screw 56. The compensating plate is mounted laterally adjustable on the frame by means of screws 49 and 50, as previously described, and the dressing head and with it the dressing guide carrying the dressing points may thus be adjusted laterally with respect to the grinding wheel.

The dressing guide to be used in the present instance, for dressing the grinding wheel 6, which is adapted to grind a 60° thread, comprises, as shown in Figs. 1—4, 6 and 7, an angularly generally V-shaped block having wings 74 and 75. This block is attached to the top plate 66 of the dressing head by means of the screw 72. Dowel pins 76—77 lock the block in predetermined angular position on the top plate of the dressing head. The wings 74—75 are each provided with a suitable aperture for accommodating the rack shafts 78—79, respectively, shaft 78 carrying teeth 80 and shaft 79 carrying teeth 81. The angular position of these rack shafts corresponds to the angle of the thread to be cut. The dressing guide

is therefore individual to the particular grinding wheel which is to be dressed.

The rack shafts are reciprocable within their corresponding openings in the wings 74-75 and each carries at its forward end a holder, as indicated at 82-83, respectively, each holder being provided with a suitable dressing point, for example, a diamond point. These holders are adjustably attached to their respective rack shafts by means of clamp screws 84-85.

The mechanism for reciprocating the rack shafts comprises a vertically disposed plunger 86 having a handle 87. The plunger extends downwardly into a suitable opening in the guide block and is provided with milled grooves forming gear or teeth sections 90-91 separated by an annular space 92. A spring 93 is placed in a central boring within the plunger. This spring tends to move the plunger upwardly. The upper gear section 90 is in operable gear engagement with the teeth on the reciprocable rack shafts 78-79. Angular oscillation of the plunger therefore causes reciprocation of the racks in opposite directions, and therewith reciprocation of the dressing points on the holders 82-83 parallel to the flanks of the grinding wheel.

In order to avoid chattering of the rack shafts and inadvertent displacement thereof, and therewith displacement of the dressing points, incident to vibrations of the machine during the thread-grinding operation, there is provided a locking feature including a stub pin 95 (Figs. 3 and 7) which is initially inserted through an opening 96 in the guide block and is held in position in the annular gear space 92 by the shank of the screw 72. This stub pin is therefore normally positioned between and slightly above any two of the teeth in the lower gear section 91, and thus prevents escape of the plunger upwardly under the pressure of spring 93, and at the same time locks the plunger against inadvertent angular displacement.

Assuming now that the setting-up of the various parts of the device, as previously discussed, has been completed, certain adjustments are made prior to starting the operation of grinding the 60° thread on the plug gage which was assumed to be the work-piece selected for explanatory purposes. These adjustments include the following:

First, the compound slide 18 is set at an angle of 29° with respect to the cross-slide, in which position the compound slide is approximately shown in the drawings. The base 12 of the mounting bracket is next set on the plate 15 at a compensating angle of 29°, the angular adjustment being facilitated by the index tongue 21 in coaction with the index markings on the periphery of the plate 15. A further angular adjustment of the mounting bracket may be made if such is required to clear the tail stock of the lathe. The screw 16 is thereupon tightened, securing the mounting bracket in proper angular position on the properly angularly adjusted compound slide.

The nut 10 and the screw 9, which have been previously preliminarily tightened, may now be loosened in order to effect angular adjustment of the grinder mechanism in a vertical plane, which adjustment is facilitated by coaction of the index tongue 26 relative to the markings on the periphery 27 of the flange 8 of the post 7. As noted before, this angular adjustment aligns the grinding wheel at the helix angle of the thread to be cut. The screw 9 is then tightened in its threaded hole in post 7 (see Fig. 5) to clamp its en-

largement 28 against the face of the member 23, thereby securing the post 7, and therefore the grinder mechanism, in angularly adjusted position.

The center alignment of the grinding wheel with respect to the work-piece is then checked and, if necessary, is corrected and properly adjusted by lifting or lowering the grinder assembly, as required, by means of the elevator screw 14. Upon completing this adjustment, the nut 10 is tightened to secure the post 7 and therewith the grinder mechanism in proper vertical position. The coaction of the screw 9 and nut 10 thus permits angular adjustment of the grinder mechanism independent of its vertical setting.

In the event that the angular adjustment of the base 12 of the mounting bracket on the compound slide necessitated only compensation for the angular setting of the compound slide with respect to the cross-slide, there will be no further adjustment required except to set the dressing points in proper alignment with the grinding wheel. This is done, if it should be necessary, by loosening the screws 49-50 (Figs. 1 and 3) and then moving the compensating plate 48 laterally with respect to the ways 43, thereby shifting the dressing head and its associated parts, including the dressing guide and the dressing points, with respect to the grinding wheel and into proper alignment therewith. It is assumed, of course, that the dressing head is in zero or neutral angular position relative to the compensating plate. The line of feed of the dressing points is now perpendicular to the axis of the grinding wheel.

If it was, however, initially necessary to adjust the mounting bracket angularly additionally for the purpose of moving the grinder mechanism to clear the tail stock, such additional adjustment displaced the line of feed of the dressing points angularly with respect to the axis of the grinding wheel, and it will therefore be necessary to restore the direction of feed perpendicular to the grinding wheel axis by angular adjustment of the dressing head on the compensating plate. In other words, if it is assumed that the compound slide was set on the cross-slide of the lathe at an angle of 29°, the mounting bracket will have to be set on the plate 15 at a compensating angle of 29°, and no other special adjustments need be made except, if necessary, as stated above, perhaps lateral shifting of the dressing head on the compensating plate to obtain proper alignment of the dressing points with the grinding wheel. But if the mounting bracket was initially set on the compound slide an additional, say, 5° so that the grinder would clear the tail stock, this additional 5° adjustment displaced the line of feed of the dressing device angularly with respect to the axis of the grinding wheel and, inasmuch as the line of feed must be perpendicular to the grinding wheel axis, the additional 5° angular setting of the mounting bracket must be compensated for by angular adjustment of the dressing device so that the line of feed of the dressing points will be perpendicular to the axis of the grinding wheel.

This adjustment is made, if required, by loosening the screw 56 (Fig. 3) and rotating the dressing head into proper angular position on the compensating plate 48. The adjustment is facilitated by the index tongue 57 in coaction with the index markings along the front edge of the plate 48.

The feed screw 60 is now rotated by operating

the knob 64 so as to position the dressing points on the holders 82—83 adjacent to but properly spaced from the grinding wheel.

The thread-grinding operation can now begin. It is, of course, assumed that the grinding wheel 6 has been previously dressed to the desired contour.

The motor 2 (Fig. 1) is started so as to rotate the spindle 4 carrying the grinding wheel 6. The head stock of the lathe is retracted and is thrown at the proper point into gear of the lathe guide spindle. The grinding wheel is then advanced into grinding position with respect to the work-piece by operating the spindle on the compound slide. As previously remarked, the feed is lateral and nearly in parallel with one side or flank of the thread to be produced. The thread-grinding proceeds for the duration of the working stroke under control of the lathe guide spindle. At the end of the working stroke the grinding wheel is retracted from the work-piece for the idler or return stroke, and is advanced again to the work-piece for the next working stroke. The amount of advance is successively adjusted by operating the spindle on the compound slide. The dressing points have been disengaged from the grinding wheel by swinging the dressing handle 87 to the right or left, as noted before, and the dressing device is thus ineffective during the thread-grinding operation and does not interfere with it.

Dressing of the grinding wheel to maintain its proper contour, which is required from time to time, is initiated by advancing the dressing points toward the grinding wheel by means of the knob 64. The plunger 86 is then depressed to release the locking pin 95 from engagement with the lower gear section 91, and is oscillated so as to reciprocate the rack shafts 78—79 and therewith the dressing points on the holders 82—83 with respect to the flanks of the grinding wheel. The amount of abrasive to be removed by such dressing is adjusted by proper angular setting of the forward end 63 of the feed screw with respect to the index marks on the front wall 58 of the dressing head. The operation is in detail as follows:

The handle 87 projecting from the dressing guide block is gripped and slight downward pressure is applied to the plunger 86 to overcome the pressure of spring 93, thus moving the plunger downwardly and the lowermost gear teeth 91 out of engagement with the stub pin 95. While the plunger is held down it is oscillated by means of the handle 87 to move the dressing points alternately back and forth along the angles determined by the setting of the rack shafts 78—79, which correspond to the angles of the flanks of the grinding wheel. The dressing points are advanced toward the grinding wheel by operation of the knob 64 of the feed screw to remove more or less abrasive, as may be required. After the grinding wheel has been properly dressed, the handle 87 is swung to the right or left, the plunger 86 is released and moves upwardly under pressure of the spring 93. The plunger locks in released position by pressure engagement of the stub pin 95 with the teeth of the lower toothed gear section 91. This locking, as previously explained, prevents inadvertent displacement of the dressing points and chattering of the rack shafts while the mechanism is employed in the thread-grinding operation.

The amount by which the dressing points are advanced during the dressing operation, which determines the amount of abrasive removed from

the grinding wheel, is noted by the operator by checking the angular position of the forward end 63 of the feed screw with relation to the index mark on the front wall 58 of the dressing head.

The grinding wheel is now again properly dressed, its contour has been restored and the thread-grinding operation can be resumed. This is done by advancing the wheel to its proper position with relation to the work-piece by means of the cross-feed screw of the lathe. The advance corresponds to the amount of abrasive which has been removed during the dressing operation. The thread-grinding is then continued under control of the lathe guide spindle, as described before.

It should be noted that the dressing of the grinding wheel is accomplished, as explained, without in any way disturbing the work-piece. This also applies to the embodiments yet to be described.

The dressing guide shown in connection with the above described embodiment is suitable for dressing the contour of a grinding wheel adapted for grinding an external 60° thread. A similarly constructed dressing guide may be used for dressing grinding wheels adapted to produce different type threads, for example, 59° or 29° threads. The difference resides in different angular position of the rack shafts in the guide block. If a different grinding wheel is used, the proper dressing guide is mounted on the dressing head, which is simply accomplished by first releasing the screw 12, removing the previously used dressing guide block, and attaching in its place the proper guide block. In other words, the dressing head remains the same for dressing practically all types of external angular grinding wheels, but the dressing of each requires attachment of a different dressing guide block provided with reciprocable rack shafts which hold the dressing points at the proper angles required for the contour of any given grinding wheel.

The steps for setting up the device and for adjusting it for the grinding of threads of different angles, as well as the grinding operation and the wheel-dressing operation, remain the same as discussed.

The contour of the grinding wheel 6, as shown in the above discussed embodiment, is assumed to be angularly symmetrical; that is, an equal amount of abrasive is symmetrically removed from each side of the wheel to form the grinding contour. Asymmetrical contours may be produced, if desired, by proper lateral positioning of the compensating plate 48 on the ways 43 of the dressing frame, and/or by proper angular setting of the dressing head on the compensating plate.

The adapter illustrated in Fig. 8 is employed when it is desired to dress grinding wheels for producing internal threads.

The adapter comprises a base plate 110 which may be mounted on the ways 43 of the dressing frame discussed in connection with the previous figures and may be attached thereto by the screws 49—50 shown in Figs. 1 and 3. The threaded opening 111 in the plate 110 is, for example, engaged by the screw 50 shown in Figs. 1 and 3. The adapter also comprises a swing frame or bracket rotatably attached to the plate 110 by means of screw 112, the bracket having a portion 113 extending in parallel with the plane of the plate 110 and an extension 114 placed at an angle thereto. The extension 114 is provided with a

rear wall 115 and ways or slide surfaces 117 and 118 to which may be attached the compensating plate 48, Fig. 3, of a dressing head constructed similarly to the one described in connection with the previous embodiment. Such compensating plate is attached on the ways 117-118 by means of screws extending from below through the elongated slots 119-120 which correspond to the slots 51-52 on the ways 43 of the previously described dressing frame. In other words, the swing bracket of this adapter constitutes a lateral extension of the dressing frame and forms ways for the attachment of the dressing head, which are inclined with respect to the general plane of the mounting of the dressing frame, and therefore inclined toward the grinding wheel. The arcuate slot in the extension 114 corresponds to the similarly placed arcuate slot in the plate 42 of the previously described embodiment (see Fig. 3). Numeral 121 indicates a feathered pin mounted in a boss 122 for the purpose of locking the swing bracket either in the position shown in Fig. 8, in which the feathered pin 121 is in engagement with a suitable hole in the base plate 110, or in alternate position shown in dotted lines in Fig. 9, wherein the feathered pin 121 is in engagement with the hole 123 shown in Fig. 8.

The use of the adapter in dressing grinding wheels for producing internal threads may be explained with reference to Fig. 9.

Numeral 130 indicates the mounting part of the dressing frame, 131 the spindle and 132 the grinding wheel. The swing bracket 113 with its inclined extension 114 carrying the ways 117-118 is shown in full lines in operative position and in dotted lines in retracted position. The dressing mechanism again comprises a dressing head constructed similarly to the one discussed before, having a top plate 133 which is movable by means of a feed screw 135 having a knob 136. The dressing head can thus be moved in a controlled manner with respect to the grinding wheel. Numeral 134 indicates the compensating plate of the structure.

The dressing guide secured on the top plate 133 of the dressing head is also constructed similarly to the one previously discussed. It comprises a generally V-shaped block having the extensions 137-138 with their rack shafts 139-140 which may be reciprocated by oscillating the plunger 141 by means of the handle 142. The rack shafts carry the dressing members 145-146. The guide is mounted on the dressing head in a similar manner as discussed before, by a screw 83a shown in the block in Fig. 9, which corresponds to the screw 72 of the previous embodiment, and is held in proper angular position by suitably placed dowel pins. The angle of the sides of the grinding wheel determines the dressing guide to be employed. Any one of a number of such guides may be mounted on the dressing head in the manner already discussed.

The steps involved in setting up and using the device illustrated in Figs. 8 and 9 are also similar to the steps previously discussed in connection with grinding external threads and dressing the grinding wheels used therefor. During the thread-grinding operation the swing fixture or bracket is in dotted-line retracted position (Fig. 9) and for the purpose of dressing is first brought into its operative full-line position. Adjustments are made, if required, as previously described. The dressing device is then in proper position relative to the grinding wheel. The

dressing of the wheel is accomplished simply by depressing the plunger 141 and oscillating it by means of the handle 142 so as to move the rack shafts 139-140 alternately toward and away from the flanks of the grinding wheel. The amount of abrasive to be removed is adjusted, as in the previous embodiment, by rotating the knob 136 so as to operate the feed screw and thereby to advance the dressing guide and the dressing points thereon by an adjusted desired amount which may be noted by indexing the calibrated forward end 135 of the feed screw with relation to a suitable index mark on the front wall 116 of the device. The operator keeps a record of the amount of abrasive removed, and upon completing the dressing operation he places the device in its retracted dotted-line position and proceeds with the thread-grinding generally as explained before.

As in the previous case, the grinding wheel 132 shown in Fig. 9 has a symmetrical contour. Asymmetrical contours may be produced, as already discussed, by proper lateral placing of the adapter on the principal dressing frame and by proper shifting of the dressing head on the ways of the adapter frame 114. The angular adjustment of the dressing head on the compensating plate may likewise be employed for this purpose.

Figs. 10 and 11 show the essential parts of a dressing head and dressing guide for contour dressing.

Numeral 150 designates the top plate of the dressing head corresponding to the top plate 66 of the previously described structure. A feed nut 151 is attached to the top plate by means of a screw 152, corresponding to the feed nut 65 and screw 67 of the previous embodiment. The feed nut is engaged by the feed screw 153 carrying a shoulder journal sleeve 154, in a similar manner as the feed nut 65 is engaged by the feed screw 60 of the first described structure. A bushing 155 is provided in the left hand end of the top plate 150 for mounting thereon the dressing guide by means of the screw 157 in a similar manner as the dressing guide of the previous embodiment is mounted by means of the screw 72, as shown in Fig. 3. The feed screw 153 projects to the outside of the dressing head and may be rotated by a suitable knob. The dressing guide mounted on the dressing head in Figs. 10 and 11 may thus be moved toward and away from the wheel to be dressed, which is diagrammatically shown in Fig. 11 at 174.

The contour dressing guide comprises a base plate 156 secured on the top plate of the dressing head by the screw 157, which is threaded into the bushing 155. The base plate 156 carries a rack, i. e., a strip-like member 159 attached by screws 160-161. This rack strip is provided with gear teeth 162. Adjacent the gear teeth 162 of the rack is mounted a templet 163 having a desired shape, e. g., the shape indicated in Fig. 10. This templet is attached by means of a screw 164 shown in Fig. 11 and is properly aligned in position by two dowel pins 165-166, shown in Fig. 10. The templet forms the guide for the lateral dressing motion to be imparted to the dressing tool 167.

The dressing tool or point 167 is mounted in an axially movable plunger 168 which is slidably secured in a guide block 169 and is prevented from rotating therein by a pin 170 which engages a guide slot 171 provided in the left hand portion of the plunger, as shown. At the right

hand end of the block 169 is provided a bushing 175 which is in threaded engagement therewith and forms a bearing shoulder for a rotatably mounted actuating member from which projects upwardly the handle 176 and downwardly a toothed section 177 forming a gear sector which is in gear mesh engagement with the teeth 162 on the stationary rack member 159.

A spring 180 is disposed within the block 169 in the space between the bushing 175 and the shoulder formed by the left hand portion of the plunger 168. This spring moves the plunger and the dressing point 167 attached thereto in left hand direction toward the grinding wheel 174 which is to be dressed. At its right hand end, which projects from the bushing 175, the plunger carries a guide or follower 181, the lower angularly disposed point of which is in contact with the shaped edge of the templet 163. The follower is secured by means of a screw 185.

The guide block 169 is laterally slidably mounted on a bar 182 which is secured to the plate 156 by screws 186—187. The alignment of the assembly is secured by gib means, including gib screws one of which is shown in Fig. 11 at 183. The bar 182 thus forms a lateral slide base engaged by ways in the guide block 169.

The operation of the above described contour grinding and dressing structure is as follows:

The dressing point 167 is advanced to the work-piece, i. e., to the grinding wheel 174 by rotating the feed screw 153. The amount of advance may be noted by the operator by observing suitable index markings on the feed screw with relation to an index line at the front of the dressing head. The handle 176 is then oscillated, thereby rotating the toothed gear sector 177 which is in gear mesh engagement with the teeth of the stationary rack 162. The dressing guide, including the block 169, and all parts attached thereto move sideways, in a lateral reciprocating motion, in response to the oscillating actuation of the handle, the movement being along the slide bar 182 on the base plate 156. The axially movable plunger 168 is moved toward the wheel 174 by the spring 180, but in the course of the sideways movement will be actuated to move in axial direction in accordance with the shape of the templet 163 which is in engagement with the point of the follower 181. The axial displacement of the dressing point 167, during its lateral reciprocating motion, is thus a function of and in accordance with the shape determined by the templet. The follower traces the contour of the templet and therefore determines the corresponding contour of the grinding wheel 174.

The contour dressing guide is shown in Figs. 10 and 11 in a position perpendicular to the axis of the grinding wheel. If desired, the guide may be positioned on the dressing head at an angle to the wheel. This is done by first shifting the block 169 sideways, to gain access to the screw 157, then loosening this screw, rotating the guide into the proper desired angular position, and again tightening the screw 157. The degree of angular adjustment may be determined by displacement of the guide with respect to the index markings on the plate 190 shown in Fig. 10, which is attached to the top plate 150 of the dressing head by means of the screws 191—192. Angular placement may also be obtained by suitable adjustment of the device on a compensating plate such as the plate 48, Figs. 1, 2, 3 of the first described structure.

It is understood, of course, that any given shape

to be ground or dressed requires a correspondingly shaped templet. By using different templets it is possible to produce numerous different surfaces, for example, spherical, ball races, valve seats, surfaces for pivot bearings, forming punches, and many other surfaces. By rotating the contour guide into a desired angular position, as previously discussed, the sides of the grinding wheel may be dressed, permitting the grinding of stepped or offset surfaces, angular surfaces, and surfaces with intricate outlines.

In Fig. 12 is shown a dressing device having three dressing points indicated at 200, 201 and 202. Some of the elements of this device are indicated separately in Fig. 13. The dressing points 200 and 202, as shown in Fig. 12, are mounted in rack shafts indicated at 203 and 204, respectively, which may be reciprocated by means of the handle 205 adapted to oscillate the plunger 206 in a similar manner as already discussed in connection with the corresponding plunger of previous embodiments. The rack shafts 203 and 204 are movably mounted in the wings 207 and 208, respectively, of the guide block. The arrangement is thus similar to those already described, except that the dressing points 200, 202 are mounted for displacement at a different angle—in this particular case, at an angle of approximately 29°.

The third dressing point 201, as indicated in Figs. 12 and 13, is mounted on a member 210 and is secured in position thereon by a screw 211. This member is secured for axial sliding displacement in the arm 212 and extends through the tubular screw 214. The member 210 may be axially shifted by rotating the tubular screw 214 which extends through a threaded hole in the arm 213. The rotation of member 210 is prevented by a screw 216 engaging a threaded hole in the arm 212 and projecting a pin-like extension into the slot 220. The structure and operation will be understood when it is considered that the member 210 is made in the form of a shaft extending at the left end slidably through the arm 212 and at the right end through the hollow tubular screw 214, into sleeve-like coupling engagement with the screw. Accordingly, when the feed screw is rotated, it is displaced axially within its thread in the arm 213 and the shaft 210 is likewise axially displaced within the arm 212. The feed screw may also extend into the shaft 210, and may carry a sleeve nut which is in splined engagement with the shaft. Any other suitable arrangement for obtaining axial displacement of the shaft 210 by rotation of the feed screw may be adopted.

The above described structure may be employed for dressing wheels used in a 29° so-called "Acme" thread. The flanks of the grinding wheel 221 are in this instance dressed by angularly reciprocating the dressing points 200 and 202 in the manner already described, by operating the handle 205 to oscillate the plunger 206; and the edge of the grinding wheel 221 is dressed by actuating the knob 215 to rotate the screw 214 which in turn causes axial displacement of the spindle or shaft member 210 and therewith of the dressing point 201 secured thereto.

Dressing guides constructed similarly to the one described in connection with Fig. 12 may also be provided for dressing wheels used in grinding square threads. The dressing points 200 and 202 would in such case be mounted for parallel reciprocation in planes perpendicular to the axis of the grinding wheel and the third dressing point 201 would be provided for recipro-

cation in parallel with the axis of the grinding wheel substantially in the same manner as indicated in Fig. 12.

The dressing guides shown in Figs. 10, 11 and 12 may be mounted on identical dressing heads, e. g., on the dressing head discussed in connection with the embodiment shown in Figs. 1 to 5, inclusive. Dressing guides for irregular or shaped contours in connection with grinding wheels for internal threads or surfaces may be mounted on dressing heads carried by the swing bracket or swing fixture discussed in connection with Figs. 8 and 9.

Changes may be made within the scope of the following claims wherein I have defined what is considered new and desired to have protected by Letters Patent of the United States.

I claim:

1. In a thread-grinding device for use with a lathe or the like, having a bracket for attachment to the compound slide of such lathe and means for adjustably holding on said bracket a mounting including a quill containing the spindle carrying at one end thereof a suitable grinding wheel for grinding contact with the work-piece on said lathe and also including driving means for said spindle, a device for dressing said grinding wheel comprising a frame projecting from said mounting radially of said quill, ways formed on said frame extending substantially in parallel with the axis of said quill, a dressing head mounted on said ways in adjustable position relative thereto, means for adjusting said dressing head angularly, and a dressing guide attached to said dressing head and carrying means for dressing said grinding wheel.

2. The combination and structure defined in claim 1, wherein said frame is removably attached to said mounting adjacent the grinding wheel secured to the spindle extending from the end of said quill.

3. The combination and structure defined in claim 1, wherein said frame is removably attached to said mounting adjacent the grinding wheel secured to the spindle extending from the end of said quill, together with means for angularly adjusting said dressing head for the purpose of disposing the dressing means thereon angularly with respect to the grinding surface of said grinding wheel.

4. The combination and structure defined in claim 1, wherein said frame is removably attached to said mounting adjacent the grinding wheel secured to the spindle extending from the end of said quill, said frame projecting forwardly with the ways thereon disposed in a plane extending substantially horizontally in parallel with the axis of said grinding wheel but radially spaced therefrom.

5. The combination and structure defined in claim 1, wherein said dressing guide comprises a member which is axially reciprocable, a toothed rack carried by said member, a plunger carrying gear means engaging said rack teeth, means for angularly oscillating said plunger to reciprocate said member, and a dressing point carried by said member for dressing engagement with said grinding wheel.

6. The combination and structure defined in claim 1, wherein said dressing guide comprises an axially reciprocable member disposed at a fixed angle bearing a predetermined relation to the angle of the thread to be produced, a toothed rack carried by said member, a plunger carrying gear means for engagement with said rack teeth,

means for angularly oscillating said plunger to reciprocate said member, a dressing point carried by said member for dressing engagement with said grinding wheel, and means for locking said plunger against accidental angular displacement incident of vibrations caused by the thread-grinding operation of the device.

7. The combination and structure defined in claim 1, wherein said dressing guide comprises a plurality of axially reciprocable members disposed at angles corresponding substantially to the angles of the flanks of the thread to be produced, gear means on said members, a plunger carrying a gear for engagement with the gear means on said members, means for oscillating said plunger to reciprocate said members for the purpose of moving the dressing means thereon with respect to said grinding wheel, and means normally engaging the gear on said plunger to lock said plunger against inadvertent displacement.

8. The combination and structure defined in claim 1, especially for producing threads by employing grinding wheels having three distinct grinding surfaces, wherein said dressing guide comprises a pair of members adapted for axial displacement and a third member adapted for displacement at an angle thereto, and means for reciprocating said members including a rotatable plunger for oscillating said pair of members and a separate shaft for displacing said third member.

9. The combination and structure defined in claim 1, especially for grinding internal threads, wherein said dressing head is mounted on ways formed on a bracket removably secured to the ways formed on said frame.

10. The combination and structure defined in claim 1, especially for producing internal threads, wherein said dressing device comprises a plate adapted for mounting on the ways of said frame, and a bracket rotatably mounted on said plate and forming ways for receiving said dressing head.

11. The combination and structure defined in claim 1, wherein a plate is laterally adjustably secured on the ways of said frame, together with means for pivotally mounting said dressing head on said plate.

12. A device for dressing grinding wheels having three grinding surfaces to maintain the contours thereof, two of such surfaces forming the flanks and one of the surfaces forming the edge of the grinding wheel, said device comprising a frame, a dressing head mounted on said frame in laterally and angularly adjustable position relative thereto, and a dressing guide mounted on said dressing head, said dressing guide comprising a pair of axially movable members carrying dressing points for dressing engagement with the flanks of said grinding wheel and an axially movable member carrying a dressing point for dressing engagement with the edge thereof, a common plunger for reciprocating said pair of members, and a separate shaft for reciprocating the member carrying the dressing point for the edge of said grinding wheel.

13. A device for dressing grinding wheels employed for grinding internal surfaces, said device comprising a frame having means forming a mounting base, a plate adjustably secured to said base, a bracket rotatably secured on said plate, a dressing head carried by said bracket, a dressing guide carried by said dressing head, dressing

means carried by said dressing guide, and means for reciprocating said dressing means.

14. A device for dressing grinding wheels employed for grinding internal surfaces, said device comprising a frame having means forming a mounting base, a plate adjustably secured on said base, a bracket rotatably secured on said plate, a dressing head secured to said bracket, a dressing guide, carried by said dressing head, said bracket being adapted for disposing said dressing head and guide secured thereto in disengaged position with the dressing means out of contact with said grinding wheel and radially spaced therefrom and alternately in working position with the dressing means disposed substantially perpendicular to the grinding wheel and adjacent the circumference thereof.

15. A device for dressing grinding wheels employed for producing shaped surfaces, said device comprising a frame, a dressing head mounted on said frame in laterally and angularly adjustable position relative thereto, a dressing guide mounted on said dressing head, said dressing guide comprising an axially and laterally movable plunger carrying dressing means at one end thereof for dressing engagement with the grinding wheel, means for holding the plunger elastically in normal position, a templet removably attached to said dressing guide and having a shape corresponding to the shape of the grinding wheel to be dressed, a follower attached to said plunger and contacting said templet, and means for displacing said plunger in accordance with the shape of said templet.

16. A device for use in dressing a grinding wheel to maintain its contour comprising a dressing guide having a pair of axially movable members each carrying a dressing point at the end thereof for dressing engagement with the flanks of the grinding wheel, gear teeth alongside each of said members, a plunger disposed perpendicular to said members and carrying a gear for meshing with the gear teeth on said members, an annular groove in the gear on said plunger, a locking member projecting into said groove, and means for normally holding said locking member in engagement with gear teeth on said plunger for the purpose of preventing accidental displacement thereof.

17. The combination and structure defined in claim 16, wherein a pin-like member constitutes said locking member, and spring means acting on said plunger for holding said pin in engagement with said gear at one side of said annular groove.

18. In combination with thread-grinding apparatus for use with a lathe or the like including a bracket adapted to be angularly adjustably attached to the compound slide of such lathe and having an adjustably secured mounting member for holding a quill carrying a grinding wheel, a device for dressing said grinding wheel, comprising a frame, means for securing said frame on said quill in radially projecting relation relative thereto, wheel dressing means carried on said frame, and means for angularly adjusting said wheel dressing means to compensate for the angular adjustment of said bracket on said compound slide.

19. The structure and combination defined in claim 18, wherein the means for adjustably securing said mounting member comprises a holder disposed in a slot in said bracket, a screw for securing said mounting member on said holder in angularly adjustable position relative thereto,

means for vertically adjusting said holder and said mounting member thereon, and means including said holder for attaching said mounting member in firm engagement with said bracket.

5 20. The structure and combination defined in claim 18, together with means for selectively positioning said wheel dressing means in operative position perpendicular to the axis of said grinding wheel and alternatively in non-operative position in a plane extending substantially in parallel with the axis of said grinding wheel.

15 21. Grinding apparatus for use with a lathe, comprising a bracket for attachment to the compound slide of a lathe and adjustable thereon in a horizontal plane, a mounting member secured to said bracket and adjustable thereon in a vertical plane, a quill carried by said mounting member and carrying a spindle supporting a grinding wheel, a frame secured to said quill, and a wheel dressing device secured to said frame, said wheel dressing device being adjustable in parallel with the axis of said grinding wheel and at an angle to the axis thereof.

25 22. The structure and combination defined in claim 21, together with index means for indicating the adjustment of said bracket on said machine tool, index means for indicating the adjustment of said mounting member on said bracket, and index means for indicating the adjustment of said wheel dressing device on said frame.

30 23. In combination, a tubular member for rotatably mounting a grinding wheel axially projecting therefrom at one end thereof, a frame secured to said tubular member and radially projecting therefrom adjacent said grinding wheel, means on said frame forming laterally directed ways thereon, a dressing head disposed on said ways, a top plate forming part of said dressing head, means for adjusting the position of said top plate, a dressing guide mounted on said dressing head, a holder axially movably disposed in said dressing guide, said holder carrying a dressing member for engagement with said grinding wheel, a toothed member associated with said dressing guide, and a handle for moving said toothed member to displace said holder for moving said dressing member relative to said grinding wheel.

35 24. In combination, a tubular member for rotatably mounting a grinding wheel axially projecting therefrom at one end thereof, a frame secured to said tubular member and radially projecting therefrom adjacent said grinding wheel, means on said frame forming laterally directed ways thereon, a dressing head disposed on said ways, a top plate forming part of said dressing head, means for adjusting the position of said top plate, a dressing guide mounted on said dressing head, a holder axially movably disposed in said dressing guide, said holder carrying a dressing member for engagement with said grinding wheel, a toothed member associated with said dressing guide, and a handle for moving said toothed member to displace said holder for moving said dressing member relative to said grinding wheel over a predetermined path which corresponds to the configuration of the surface of the grinding wheel which is to be dressed by said dressing member.

40 25. In a device for dressing a grinding wheel, a dressing member, a holder for carrying said dressing member, a guide for axially movably mounting said holder, a toothed member associated with said guide, handle means for moving said toothed member to displace said holder and the dressing member carried thereby, a dressing head carrying

a top plate, means for adjustably mounting said guide on said top plate, means for adjusting the position of said top plate, and means for adjustably mounting said dressing head carrying said top plate.

26. The structure and combination defined in claim 25, together with a frame for receiving said means for adjustably mounting said dressing head carrying said top plate, mounting means for said frame, and means for adjustably securing said mounting means.

27. In a thread-grinding apparatus for use with a lathe or the like, having a bracket for attachment to the compound slide of such lathe and means for adjustably holding on said bracket a mounting including a quill containing the spindle carrying at one end thereof a suitable grinding wheel for grinding contact with the work-piece on said lathe and also having driving means for said spindle, a device for dressing said grinding wheel comprising a frame, means for securing said frame on said quill, a compensating plate adjustably mounted on said frame, a dressing head adjustably mounted on said compensating plate, a dressing guide secured to said dressing head and carrying means for dressing said grind-

ing wheel, index means on said bracket for adjusting said bracket angularly on said compound slide, and index means on said dressing head for adjusting the angular position thereof on said compensating plate.

5 STANLEY WALLACE.
